FISHING LURE BOX

Hugh C. N. McGee, Dry Ridge, Ky.

Application April 5, 1954, Serial No. 29,858

Term of patent 14 years

(Cl. D58—12)

Fig. 1

Fig. 2

To all whom it may concern:

Be it known that I, Hugh C. N. McGee, a citizen of the United States, residing at Dry Ridge, in the county of Grant and State of Kentucky, have invented a new, original, and ornamental Design for a Fishing Lure Box, of which the following is a specification, reference being had to the accompanying drawing, forming a part thereof.

I claim:

The ornamental design for a fishing lure box, substantially as shown.
